UNITED STATES PATENT OFFICE.

ALVAH F. WILSON, OF CINCINNATI, OHIO, ASSIGNOR OF ONE-HALF TO JAMES H. McCABE, OF CINCINNATI, OHIO.

DRAFT INDICATING AND RECORDING GAGE.

1,236,524.

Specification of Letters Patent. Patented Aug. 14, 1917.

Application filed October 13, 1915. Serial No. 55,658.

To all whom it may concern:

Be it known that I, ALVAH F. WILSON, a citizen of the United States, and a resident of the city of Cincinnati, in the county of 5 Hamilton and State of Ohio, have invented certain new and useful Improvements in Draft Indicating and Recording Gages, of which the following is a full, clear, and exact description, reference being had to 10 the accompanying drawing, forming part of this specification.

My invention relates to gages designed for indicating and recording variations in air pressure and the like, and it is especially designed to provide a convenient and effective device to indicate at a glance the air draft over the grate of a furnace and to record the variations of same so as to insure a proper maintenance of the fire on the 20 grate.

The invention consists of that certain novel construction and arrangement of parts whereby the variations of pressure are indicated on an enlarged scale directly from 25 the variations of height of a column of liquid without the necessity of any multiplying gears or complicated mechanism, and in which a very simple and effective means is provided.

30 In the drawing,

Figure 1 is a front elevation of my gage with the front door partly broken away not showing the chimney gage connections.

Fig. 2 is a horizontal section.

35 Fig. 3 is a vertical section of the operating mechanism for the indicator gage, showing the lever for the recording damper gage, but none of its connections.

The working parts are inclosed in a box 40 or casing 1, rectangular in shape, and provided with a front door 2 for access to the working parts, and also with a lateral casting 3 for the indicating dial and indicating hands.

45 Mounted in the bottom of the case are the two vessels 4, 5, connected by the tube 6, in which vessels is placed the liquid, preferably oil, 7, adapted to be acted upon by the air suction.

50 The container 4 is closed at the upper end and connected by the tube 8 with the coupling or nipple 9, which extends through the wall of the casing, and with which connection is made with a draft tube 10 open-

ing into the furnace at the point the air 55 suction is to be taken. The other vessel 5 is open at the top and is provided with a float 12. The float 12 is suspended by the rod 13 pivoted at 15 to the lever arm 14. This lever arm is pivoted to the casing at 60 16, and extends out laterally through the casing 3 behind a sight opening where a dial 17 is provided and where the lever is provided with a pointer 18. The ratio of distances between the pointer 18 and the fulcrum of the lever 14 and between said fulcrum and the connection with the rod 13 is about 30 to 1, so that a very slight movement of the float will be indicated clearly 65 on the dial.

In order that the gage may be read from either side, as the furnaces may be arranged in gangs, and a gage provided extending out from the front face plate for each furnace, the casing has a window 45 on each side, 70 and the scale is imprinted on both sides of the dial. The lever 14 is provided with an additional pointer 46 for the opposite side of the dial.

The lever arm 14 is provided with a 80 counter weight 19 screwthreaded on the inner end of the arm so as to adjust the weight with reference to the float.

Pivoted to the casing above the lever 14 is a finger arm 20 provided with a pen or 85 pencil 21, whose point bears on a disk 22 furnished with a record sheet. The disk is mounted on the central shaft 23 and is driven slowly by clock work, not shown. The finger 20 is coupled to the lever arm by 90 the connecting bar 24, so that the position of the lever arm as affected by the movement of the float will be recorded on the record sheet.

It will be evident that with liquid in the 95 vessels 4 and 5 and the tube 6 connecting the two vessels, the suction through the draft tube 10 will tend to form a vacuum in the vessel 4 and air pressure on the float will cause the float to descend and the pressure to be indicated on the dial and also on the record sheet. 100

It will also be evident that when in use, evaporation would affect the level of the liquid in the pressure vessels, and the result 105 would be that this would affect the accuracy of the gage.

In order to maintain a constant level and

prevent evaporation destroying the accuracy of the gage, I provide an accumulator vessel 25 located above the tube 6 and provided with several small openings 27 in the bottom of the vessel opening into the tube.

5 An air opening 28^a is provided through the side of the vessel 25, and the oil or other liquid is poured into this vessel up to the air opening and thus fills the vessels 4 and 10 5 to the same level. An air tight cap or plunger 28 is provided for the accumulator, screw threaded on a central pin 29, so that the cap can be always maintained in a position resting on the oil in the accumulator, 15 and to maintain an air tight fit of the cap, it is provided with a sealing washer 30.

Small openings 27 are provided for the passage of oil from the accumulator, so that the movement of the oil into and out of 20 the accumulator shall be slow to prevent vibrations in the level of the liquid as the level is affected by the air draft. If the oil from the accumulator had an unobstructed passage into the tube 6, the tendency would 25 be to cause a momentary raising and lowering of the liquid in the float chamber until the new level was obtained, caused by the exhaustion of the air from the vessel 4. I have found that the small openings prevent 30 this tendency to vibration, and I am inclined to believe that the result of the small holes is that the accumulator will act as a retarder. I have proven by actual tests, however, that the large hole from an 35 accumulator causes vibration, and a small one or small ones do not do so.

As the gage is intended for a draft gage in a furnace to determine that the grate fire is maintained in proper condition, the fireman might maintain a proper level for the gage, not by regulating the fire, but by regulating the damper in the flue. Therefore to record the fact that the draft through the flue is properly maintained, I provide in 45 connection with the draft gage, a similar gage for the draft in the flues. The vessels 4, 5 and 25 are duplicated in the back of the case at 31, 32 and 33, with an outlet from vessel 32 through the nipple 34 and tube 35 to the flue. A float 36 is provided 50 connected to the lever 37, pivoted to the casing and provided with a counterweight 38, and this lever is coupled by the connecting bar 39 the same having an elbow therein 55 (Fig. 2) to the finger 40, carrying a pen or pencil 41, which also bears on the record sheet on the disk 22. It will be obvious that with this construction the draft in the damper will be also registered on the record 60 sheet, and by reading both records together it can be determined whether there has been any manipulation of the flue dampers, in order to obtain the proper draft through the grate bars.

65 In order that the fireman may have some-

thing to indicate the proper pressure to be maintained for the furnace draft, I provide an indicating pointer 42, mounted on the turn button 43, so that this pointer can be set in the proper position. This pointer 70 shows on each side of the dial, as shown in Fig. 2.

In setting up the gage for use, the accumulator is filled with oil to the air opening and then the cap is screwed down so 75 that the accumulator is filled with oil without any air space. As I have already pointed out, it is evident that evaporation would cause a diminution of the amount of oil or liquid in the device, and this would of course change the level of the float and the position of the indicating lever. Therefore as evaporation takes place, the cap of the accumulator is given a slight downward turn to bring back the level of the oil in 80 the float chamber to the proper position.

Having thus described my invention, what I claim as new and desire to secure by Letters Patent, is:—

1. In a device of the character described, a casing having a laterally extended arm thereon, a scale in the arm visible from both sides thereof, an indicator lever in said arm, pointers on the lever adapted to lie over each side of the scale to show thereupon 90 from both sides of the arm, and a gage in said casing having liquid reservoirs, and means operated thereby for controlling the lever, whereby said arm may extend out from a furnace for easy reading of the indications.

2. In a device of the character described, the combination with a casing, a laterally extending arm thereon, an indicator in the arm, a draft gage in the casing comprising 105 a closed cylinder having connections for a pipe to a draft flue, an open cylinder having a float therein connected with the indicator, a passage between said two cylinders, an accumulator cylinder communicating 110 with said passage for maintaining an oil level in the cylinders, a recording arm connected to the indicator arm, a gage comprising like cylinders, passages and accumulator set in said casing alongside of the first mentioned gage, a recording arm operated by 115 said gage, a single chart for both recording arms, and connections from the last mentioned gage for a damper pipe, substantially as and for the purpose described.

3. In a draft gage having an indicator, a pair of liquid containers, one to be connected to the draft, and a float in the other for operating the indicator, there being a passage between said receptacles, and an accumulator for liquid having constricted connections with said passage, for the purpose described.

4. In a device of the character described, the combination with two liquid receptacles,

means forming a passageway between them, one receptacle sealed from and the other open to the air, a float for the open vessel, and means for connecting a draft pipe to the closed vessel, and a liquid in the receptacles adapted to change its level with variations in the suction on the draft pipe, an inde-

pendent sealed reservoir with liquid to fill the same, there being passageways therefrom to the passageway between the receptacles, and an adjustable cap to force the liquid from the reservoir into the receptacles as the quantity decreases by evaporation. 10
